UNITED STATES PATENT OFFICE.

GEORGE HILLIARD VINCENT, OF SPUR, TEXAS.

COTTON-PICKING DEVICE.

1,366,436.

Specification of Letters Patent. Patented Jan. 25, 1921.

Application filed February 18, 1920. Serial No. 359,559.

To all whom it may concern:

Be it known that I, GEORGE HILLIARD VINCENT, a citizen of the United States, residing at Spur, in the county of Dickens and State of Texas, have invented certain new and useful Improvements in Cotton-Picking Devices, of which the following is a specification, reference being had to the accompanying drawings.

10 This invention relates to certain improvements in cotton picking devices, and it is an object of the invention to provide a novel and improved device of this general character which may be readily and conveniently engaged with the outer extremity of the digit of the hand.

Another object of the invention is to provide a novel and improved device of this general character including a digit encircling band provided with means to afford protection to the opposite sides of the digit and wherein a picking element is carried by the band.

25 The invention consists in the details of construction and in the combination and arrangement of the several parts of my improved cotton picking device whereby certain important advantages are attained and the device rendered simpler, less expensive 30 and otherwise more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

40 Figure 1 is a view in elevation diagrammatically illustrating a hand having applied thereto a picking device constructed in accordance with an embodiment of my invention;

45 Fig. 2 is a view in top plan of one of my improved devices in applied position;

Fig. 3 is an enlarged view in plan of one of my improved devices in an extended or flattened condition;

50 Fig. 4 is a view in top plan of a picking device constructed in accordance with a further embodiment of my invention;

Fig. 5 is a view in bottom plan of the device as illustrated in Fig. 4; and

55 Fig. 6 is a view in side elevation of a device as disclosed in Figs. 4 and 5.

As disclosed in the accompanying draw-

ings, B denotes a split band adapted to encircle the digit of a hand adjacent the top thereof. One end portion of the band is provided with the longitudinally spaced and transversely disposed slots 1 through which is adapted to be threaded the opposite end portion of the band whereby said band B may be adjusted in accordance with the requirements of practice and in a manner to assure an effective engagement with the digit of the hand upon which it is applied.

The band B, at substantially diametrically opposed points, is provided with the rearwardly directed arms or extensions 2 which are adapted to overlie the side faces of the digit and to afford protection therefor. The extremities of the arms or extensions 2 are provided with the slots or openings 3 through which is directed a second band B' adapted to encircle the digit. The band B' is split and one end portion thereof is provided with the longitudinally spaced openings 4 through which is threaded the opposite end portion of the band B' so that said band B' may be readily adjusted as the occasions of practice may necessitate.

The central portion of the band B and substantially midway between the arms or extensions 2 is provided with the openings 5 spaced in a direction circumferentially of the band B and through which extend the free end portions of a picking element E. The element E is substantially U-shape in form and the central part of its intermediate portion *a* is pinched or otherwise flexed to afford an outstanding loop or extension 6.

Coacting with the band B and the side members *b* of the element E is a bracing strap or member M which operates to maintain the element E substantially rigid so that the efficiency of such element E during a working operation is materially increased.

In practice it is intended that one of my improved devices be applied to the extremities of all of the digits of the hand so that, when necessary, a pinching action may be created to remove the cotton, although this is not necessary under all conditions as the formation or shape of the element E in a majority of instances permits the cotton to be readily removed by the use of a single digit.

As is well known, cotton is soft and springy and the bolls are of different sizes. My improved clamping element E can be readily adjusted as required by pressing

upon the side members *b* of the element *E* or separating the same and which operation is due to the fact that the element *E* is pliable and possesses a certain degree of inherent resiliency.

The bands *B* and *B'*, together with the arms or extensions *2*, also operate to effectively protect the digit of the hand against the burs and which burs, as is well known, 10 are hard and sharp.

In the embodiment of my invention as illustrated in Figs. 4, 5 and 6, the band *A* is substantially the same construction as the band *B* hereinbefore referred to and is provided with the rearwardly directed arms or extensions *2'* provided with the slots *7* having their major axes extending in a direction circumferentially of the band *B*. The extremities of a protecting strap *8* are 20 threaded through said slots *7* and said strap extends across the back of a digit to provide a further shield or guard.

E' denotes a picking element of substantially the same type as the element *E* hereinbefore referred to, and coacting with the side members *b'* of said element *E* is a loop *9* adapted to bridge the back of a digit whereby said loop serves to maintain the element *E'* in requisite position. One end 30 portion of the loop *9* is provided with an extension *10* in locking engagement with the band *A* through a slot *1^a* therein whereby further means are provided to maintain the element *E'* substantially rigid.

From the foregoing description, it is thought to be obvious that a cotton picking device constructed in accordance with my invention is particularly well adapted for use by reason of the convenience and facility with which it may be assembled and operated, and it will also be obvious that my invention is susceptible of some change and modification without departing from the principles and spirit thereof, and for this reason, I do not wish to be understood as limiting myself to the precise arrangement and formation of the several parts herein shown in carrying out my invention in practice except as hereinafter claimed.

I claim:—

1. A cotton picking device comprising a digit engaging member and a picking element consisting of a length of material arranged in substantially a U-shape and having its extremities secured to said member. 55

2. A cotton picking device comprising a digit engaging member and a picking element consisting of a length of material arranged in substantially a U-shape and having its extremities secured to said member, 60 said length of material being bendable.

3. A cotton picking device comprising a digit engaging member and a substantially U-shaped picking element having its extremities secured to said member, the central portion of the intermediate part of said element being provided with an extension. 65

4. A cotton picking device comprising a digit engaging member and a substantially U-shaped picking element having its extremities secured to said member, the central portion of the intermediate part of the element being provided with an outwardly extending loop. 70

5. A cotton picking device comprising a digit engaging member and a substantially U-shaped picking element having its extremities secured to said member, said digit engaging member being provided with extensions adapted to overlie the side portions of the digit to which the member is applied. 75

6. A cotton picking device comprising a digit encircling member and a substantially U-shaped picking element having its extremities engaged with the digit encircling member. 85

7. A cotton picking device comprising a digit encircling member and a substantially U-shaped picking element having its extremities engaged with a digit encircling member, said member being split, the extremities thereof being provided with means whereby the same may be adjustably connected. 90

In testimony whereof I hereunto affix my signature.

GEORGE HILLIARD VINCENT.
